PNEUMATIC SERVO-MOTOR

Earl R. Price and Edward E. Hupp, South Bend, Ind., assignors to Bendix Aviation Corporation, South Bend, Ind., a corporation of Delaware

Application September 19, 1955, Serial No. 534,951

3 Claims. (Cl. 121—41)

The present invention relates to a pressure producing device, and more particularly to a control valve therefor.

Devices of the above mentioned type usually employ control valves housed therein and actuated by means of a control member projecting externally of the device.

Devices of this type are used in one application as the actuator for hydraulic braking systems of motor vehicles, in which case the control member is usually pinned to a conventional foot pedal lever which transmits a certain amount of non-linear movement to the control member. With such an arrangement, the control member cannot be guided with respect to the housing of the servomotor, and the control member must be connected to the control valve structure by means of a swivel connection, adapted to permit a slight amount of rotational movement between the control member and the control valve structure. Sufficient friction is produced in swivel connections to transmit yawing forces to the control valve structure, and as a result complications occur. The art has become highly competitive and is ever seeking devices which are inexpensive to manufacture and which will give longer trouble free operation.

An object of the present invention is the provision of a new and improved control valve structure for pressure producing devices and the like, comprising three concentrically arranged valve members, the center member of which is attached to one of the other members in a manner permitting universal movement with respect thereto, and the inner and outer members of which are guided with respect to each other.

Another object of the invention is the provision of a new and improved pneumatic servo-motor having a control valve structure of the above described type in which either the inner or outer member is swivelly connected to and moved by a non-guided control member, and which control valve structure is less subject to failures, and has a longer service life than do corresponding prior art devices.

A further object of the invention is the provision of a pneumatic servo-motor having a new and improved control valve structure of the above described type which is simple in design, rugged in construction, and inexpensive to manufacture.

The invention resides in certain constructions and combinations and arrangements of parts; and further objects and advantages will be apparent to those skilled in the art to which the invention relates from the following description of the preferred embodiment described with reference to the accompanying drawing forming a part of this specification, and in which:

Figure 1 is a longitudinal cross sectional view of a power-assisted master cylinder embodying the principles of the present invention; and

Figure 2 is a fragmentary enlarged sectional view of the control valve of the device shown in Figure 1.

Referring now to the drawing and particularly to Figure 1, the pressure producing device shown therein comprises a hydraulic cylinder A positioned on one end of an

2

atmospheric suspended power cylinder B, the latter having therein a movable wall C adapted to operate a fluid displacement member D which projects into the adjacent end of the hydraulic cylinder A. Movement of the movable wall C is controlled by novel valve means E positioned on the movable wall and adapted to regulate the pressure differential applied across the movable wall. The valve means E is in turn actuated by control member F which projects externally of the power cylinder and which is adapted to be moved by an operator's foot. Movement of the control member F into the power cylinder B causes the control valve E to close atmospheric valve G and open vacuum valve H to admit vacuum to chamber J—thereby causing the piston C to force the fluid displacement member D into the hydraulic cylinder A to force the hydraulic fluid normally contained therein into a hydraulic system, not shown, as for example the braking system of an automobile.

For a complete description of the construction and operation of some of the details of the hydraulic cylinder A shown in the drawing, reference may be had to Patent No. 2,690,740 granted to E. E. Hupp, October 5, 1954.

The movable wall C shown in the drawing is made from two sections, a front section 10 and a rear section 12 fastened together by bolts 14 so as to form a diaphragm chamber 16, as described in the above referred to patent. The front section 10 is provided with an axially extending boss 18 having a central opening or valve chamber 20 therein in which the valve structure E is located. An annular valve seat 22 is provided adjacent the inner end of the valve chamber 20 by slightly enlarging or counterboring the inner end of the valve chamber 20 as at 24, and an annular valve member 26 is arranged to cooperate with the seat 22.

The annular valve member or ring 26 is, in general, a cylindrical sleeve shaped member having spaced apart radially outwardly extending flanges 30 and 32. The flange 32 is adapted to abut seat 22 and the flange 30 forms a seal with the sidewalls of chamber 20 to provide an enclosed annular chamber 34 which is supplied with vacuum as by the flexible connection 36. The annular valve member 26 is adapted to be moved axially to the right to separate the inner flange 32 from seat 22. The valve member 26 need not be constructed as illustrated but may, for example, be made from a single piece of flexible material, such as rubber or the like, or it may be made from a one-piece, rigid member whose forwardly positioned flange 30 slidably and sealingly engages the sidewalls of the chamber 20.

The preferred construction shown in the drawing comprises the annular valve member 26 made from a rigid metallic sleeve or main body portion 38, having a radially extending rigid flange 32 on its inner end that is provided with a seating surface 40 of yieldable material, and a flexible flange 30 on its outer end. The radially outer portion of flange 30 is positioned in a recess 42 in the sidewalls of chamber 20 and is clamped therein as by clamping plate 44; and the radially inner end of the flange 30 is positioned over and bonded to a slightly turned portion 46 of the sleeve 38. The valve member 26 is held in its valve closing position by a light coil spring 48 positioned between the inner flange 32 and a plate 49 attached to the inside of the front section 10.

As is fully explained in the above referred to Patent No. 2,690,740, atmospheric pressure is always supplied to the forward chamber 50 of the power cylinder B, i. e., the chamber closest to the operator or left hand chamber as viewed in the drawing, by tubing connection 52. Passage of this pressure from the front power cylinder chamber 50 to the rear power cylinder chamber 54 through the passageway provided by the central opening of annular valve member 26, diaphragm chamber 16, and passage

70

56, is controlled by a valve closure member 58 having an annular valve seat 60 thereon adapted to abut flange 30 of the annular valve member 26 and form a seat therewith. The valve closure member 58 shown in the drawing comprises a cylindrical shaped portion 62 which extends through the central opening of the annular valve member 26 and which has an enlarged cylindrical portion 64 on its outer end which carries the annular valve seat 60. The center of the valve closure member 58 is bored out to provide a socket 66 to receive the ball shaped end 68 of a push rod or valve actuating member F, the other end of which is pinned to an automobile brake pedal or treadle 72.

In order to maintain the axially slidable valve closure member 58 concentric with respect to the valve member 26, two axially spaced plate members 49 and 76 are provided with central openings 82 and 80 respectively. These plate members are securely attached in any suitable manner, such as by screws 78 to the boss 18 of the front section 10 and insure a positive guide for the member 58 slidably received in the central openings of the plate members. Passages 84 in each of the plate members 49 and 76, establish communication between chambers 50 and 54 when the valve G is in the position shown in Figure 1.

Operation

The power operated master cylinder A is shown in Figure 1 of the drawing in its retracted or non-brake applying position. In this position, air admitted through connection 52 is permitted to flow from the front power cylinder chamber 50, past the valve seat 60, through the annular space between valve closure member 58 and the annular valve member 26, through diaphragm chamber 16 and passage 56, to the rear power cylinder chamber 54. Upon depressing the pedal 72, push rod F moves valve closure member 58 inwardly to bring its annular valve seat 60 to bear against flange 30 of the annular valve member 26, as shown in Figure 2, thereby closing off atmospheric communication to the rear power cylinder chamber 54. Continued inward movement of valve closure member 58 forces the annular valve member 26 inwardly to lift its inner flange 32 away from the annular valve seat 22 to permit communication between the vacuum chamber 34 and the rear power cylinder chamber 54. As air is evacuated from the rear power cylinder chamber 54, the movable wall C is forced inwardly by the differential pressure thereacross. If the operator holds the push rod F in one position, the movable wall C carries the annular valve seat 22 inwardly to abut flange 32 of the annular valve member 26. In this position, the valve seat 60 of the valve closure 58 still abuts flange 30 of the annular valve member 26 and a lapped position of both valves is reached. In this position of equilibrium, air will neither be flowing in nor out of the rear power cylinder chamber 54, and the fluid displacement member D will have forced a predetermined amount of brake fluid into the braking system of the vehicle. If more braking force is required, the brake pedal may be further depressed to cause more brake fluid to be forced into the braking system of the vehicle; and if less braking effort is required, the pedal may be partially retracted, until a new lapped position of the valve structure is assumed, all in a manner well known in the art.

It will be seen that the objects heretofore enumerated as well as others have been accomplished, and that there has been provided a new and improved control valve structure for a pneumatic powered master cylinder and the like comprising three concentrically arranged valve members, the center member of which is attached to one of the other members in a manner permitting universal movement with respect thereto, and the inner and outer members of which are guided with respect to each other; such that the valve members automatically and correctly position themselves with respect to each other, even though they are actuated by a non-guided control member.

While the preferred embodiment of the invention has been described in considerable detail, we do not wish to be limited to the particular construction shown which may be varied within the scope of the invention, and it is the intention to cover hereby all adaptations, modifications and arrangements thereof which come within the practice of those skilled in the art to which the invention relates.

We claim:

1. A pneumatic fluid pressure servo-motor comprising a power chamber, a movable wall in said power chamber, an axially extending valve chamber in said movable wall, a first coaxially positioned annular valve seat facing rearwardly of the rearwardly positioned end of said axially extending chamber, a first axially movable generally tubular valve member in said axially extending valve chamber having generally radially outwardly extending flange portions adjacent its opposite ends, one of said flange portions being rearwardly positioned from and adapted and arranged to overlie and close off said first annular valve seat, and the other of said flange portions being a flexible member the radially outer edges of which are rigidly supported by the walls of said valve chamber to form an enclosed chamber, a second valve member having a first portion projecting through the axially extending opening of said first tubular valve member and having an enlarged portion positioned forwardly of the forward flange of said first tubular valve member, a second annular rearwardly facing valve seat on said enlarged portion of said second valve member adapted and arranged to abut the forward flange of said first tubular valve member and form a seal therewith, a control member projecting into said servo-motor and swivelly connected to said second valve member, first means guiding said first portion of said second valve member for axial movement, and second means guiding said enlarged portion of said second valve member, said first and second means being supported by the movable wall and being spaced on opposite ends of said first valve member.
2. A pneumatic fluid pressure servo-motor comprising a power chamber, a movable wall in said power chamber, an axially extending valve chamber in said movable wall, a first coaxially positioned annular valve seat facing rearwardly of the rearwardly positioned end of said axially extending chamber, a first axially movable tubular valve member in said axially extending valve chamber having generally radially outwardly extending flange portions adjacent its rearwardly and forwardly positioned ends, the rearwardly positioned flange portion of said valve member being positioned rearwardly of and constructed and arranged to overlie and close off said first annular valve seat, and the forwardly positioned flange portion of said valve member being a diaphragm the outer edges of which are rigidly supported by the walls of said valve chamber to form an enclosed chamber, a second axially positioned valve member having a portion projecting through the axially extending opening of said first tubular valve member and having an enlarged portion positioned forwardly of the forward flange of said first tubular valve member, a second rearwardly facing annular valve seat on said enlarged portion of said second valve member constructed and arranged to abut the forward flange of said first valve member and form a seal therewith, a control member projecting into said servo-motor and swivelly connected to said second valve member, first means guiding the rearwardly positioned end of said second valve member for axial movement, and second means guiding the enlarged portion of said second valve member for axial movement, said first and second means being supported by the movable wall and being spaced on opposite ends of said first valve member.
3. A pneumatic fluid pressure servo-motor comprising a power chamber, a movable wall in said power chamber, an axially extending valve chamber in said movable wall, a first coaxially positioned annular valve seat facing rearwardly from the rearwardly positioned end of

said axially extending chamber, a first axially movable tubular valve member in said axially extending valve chamber having generally radially outwardly extending flange portions adjacent its rearwardly and forwardly positioned ends, the rearwardly positioned flange portion of said valve member being positioned rearwardly of and constructed and arranged to overlie and close off said first annular valve seat, and the forwardly positioned flange portion of said valve member being a diaphragm the outer edges of which are clamped to the walls of said valve chamber to form an enclosed chamber, a second valve member having a first generally cylindrical portion projecting through the axially extending opening of said first tubular valve member and having an enlarged generally cylindrical portion positioned forwardly of the forward flange of said first tubular valve member, a second rearwardly projecting annular valve seat on said enlarged portion of said second valve

member constructed and arranged to abut the forwardly positioned flange of said first valve member and form a seal therewith, a control member projecting into said servo-motor and swivelly connected to said second valve member, a first guide plate connected to said movable wall and having a hole therein adapted to receive the first generally cylindrical portion of said second valve member, and a second guide plate connected to said movable wall and having a hole therein adapted to receive the enlarged generally cylindrical portion of said second valve member.
